(57) **CLAIM**

I claim the ornamental design for a reversible cane cover, as shown and described.

DESCRIPTION

FIG. 1 is a front view showing the first pattern and the hook portion of the hook-and-loop fastener.

FIG. 2 is a back view showing the second pattern and the loop portion of the hook-and-loop fastener.

FIG. 3 is a side elevation view of the partially open reversible cane cover showing the first pattern on the outside and the second pattern on the inside.

FIG. 4 is a side elevation view of the partially open reversible cane cover showing the second pattern on the outside and the first pattern on the inside.

FIG. 5 is a top view of the reversible cane cover.

FIG. 6 is a bottom view of the reversible cane cover; and, FIG. 7 is a front view showing the reversible cane cover in use.

The ends of the reversible cane cover are shown broken away to indicate that no particular length of reversible cane cover forms a part of the claimed design.
